DRAIN CABINET

Daniel R. McGlohon, Winton, N. C.

Application September 15, 1937, Serial No. 164,076

1 Claim. (Cl. 221—69)

The invention relates to a cabinet and more especially to a drain cabinet.

The primary object of the invention is the provision of a cabinet of this character, wherein the same has arranged therein a series of compartments, these being independent of each other and are formed with hopper-like drain bottoms provided with drain faucets so that liquid held within such compartments can be conveniently and easily drained from the containers therefor, the cabinet being useful for the draining of liquid such as water, syrups, greases, oils or the like as well as for drying purposes of the containers or the like carrying such liquid.

Another object of the invention is the provision of a cabinet of this character, wherein in each compartment is arranged a releasable rack for the carriage of receptacles having liquid therein to be dispensed or drained from such compartment, the cabinet being useful in homes, hospitals, garages, gasoline stations or other places for dispensing of liquids.

A further object of the invention is the provision of a cabinet of this character, which is simple in construction, thoroughly reliable and efficient in operation, portable, neat in appearance, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is a vertical longitudinal sectional view through a cabinet constructed in accordance with the invention.

Figure 2 is a fragmentary transverse sectional view thereof.

Figure 3 is a perspective view of the basket-like rack removed from one of the compartments of the cabinet.

Similar reference characters indicate corresponding parts throughout the several views in the drawing.

Referring to the drawing in detail, A designates generally a portion of the cabinet constituting the present invention and is in the form of a stand 10 having corner legs 11 provided with wheel casters 12 of conventional kind. In the upper portion of the stand 10 arranged side by side is a plurality of receivers 13, these forming independent compartments 14 interiorly thereof and open through the top of the stand while the lower portions of said receivers are formed with

hopper shaped bottoms 15 carrying at their lowermost portions valved cut-offs or faucets 16 so that the compartments 14 can be properly drained on the opening of said faucets. The stand 10 in the lower portion thereof carries a shelf 17 on which can be placed receptacles 18 which, when below the faucets on the turning on of the latter, will allow the drainage from the compartments 14 to flow into said receptacles 18.

In each compartment 14 is arranged a rack including a reticulated bottom 19 having upstanding corner hangers 20, these at their upper ends being provided with hooks 21, which are adapted to engage with the walls of the receivers at opposite ends thereof for the suspension of the rack within the compartment. The rack 19 is open at the sides and ends and is provided with longitudinal and transverse braces 22 and 23, respectively, these being unitary with the hangers 20 while swingingly fitted with the braces 22 are loop handles 24 so that the racks can be readily removed from the compartment 14 when hung within the receivers 13. Adapted to be placed on the racks are containers 25 holding liquids, these being open in a downward direction to allow full emptying of the contents of such receivers when upon the rack.

The stand 10 at its top carries a vertically swinging lid or cover 26 hanging at 27 and on the opening thereof free access can be had to the receivers 13 which are open at their upper ends or tops. These receivers 13 are permanently built within the stand 10 and likewise the shelf 17 is permanently built therein.

When the containers 25 have been emptied when within the racks, the same can be readily dried and their contents fully drained therefrom, the drainings being discharged through the faucets 16 into the receptacles 18, which are placed upon the shelf 17 in the stand 10.

The receivers 13 are formed in a single body unit 28 made from sheet metal or the like.

What is claimed is:

A cabinet of the character described comprising a stand, a drain compartment arranged in said stand and having a hopper shaped bottom, a valve arranged below said compartment within said stand, a reticulated rack removably suspended within the compartment, upstanding hooks arranged on said rack and separably engageable with the walls of said compartment for the suspension of the rack therein, and a cover carried by the stand for closing the compartment at its top and holding the hooks on the rack engaged with the walls of said compartment.

DANIEL R. McGLOHON.
